OSCAR F. MANN, OF INDIANAPOLIS, INDIANA.

MORTAR-GAGING TROWEL.

1,321,532.

Specification of Letters Patent.

Patented Nov. 11, 1919.

Application filed July 26, 1918. Serial No. 246,895.

To all whom it may concern:

Be it known that I, OSCAR F. MANN, a citizen of the United States, residing at Indianapolis, in the county of Marion and State of Indiana, have invented a new and useful Mortar-Gaging Trowel, of which the following is a specification, reference being had to the accompanying drawings, and to the letters and figures of reference marked thereon.

This invention relates to a mason's trowel and has reference more particularly to a trowel that is designed to be used by hand generally for laying mortar, and especially for laying the mortar compactly and uniformly to a measured width and thickness.

An object of the invention is to provide a mason's trowel which shall be so constructed as to enable a workman to facilitate the building of walls, and to obtain the greatest advantages in the matter of accuracy of work and also in efficiency and economy in the use of mortar. Another object is to provide a hand trowel which shall have large capacity and be adapted to carry mortar without permitting particles of the mortar to fall off and become lost or wasted, in order that the maximum results may be obtained from the workman's time and efforts. A further object is to provide a mason's trowel which shall be of such construction as to enable the mason, when placing mortar upon a wall under construction, to not only place a layer of mortar of uniform thickness and width but to also cause the mortar to be forced down into the joint openings between the bricks or stones of the course of bricks or stones that may be uppermost. A still further object is to provide a mortar-gaging trowel which shall be adapted to be carried by hand and used in the building of walls in an efficient manner not only by experts but by those having limited experience in laying mortar, which trowel shall be adapted to be used also by hand in the usual manner for various purposes and be durable and economical in use.

With the above-mentioned and other objects in view, the invention consists in a trowel having low side-boards adapted to perform the functions of runners and gages for determining the thickness and width of a layer of mortar, the forward portion of the trowel having a projecting point extending downward toward the plane of the edges of the side-boards to cause a longi-

tudinal groove or depression in the surface of the layer of mortar; and, the invention consists also further in the trowel having certain novel features of construction and combinations and arrangements of parts, as hereinafter particularly described and further defined in the accompanying claims.

Referring to the drawings,—Figure 1 is a perspective view of the new trowel as preferably constructed; and, Fig. 2 is a perspective view of a portion of a wall and the trowel thereon arranged in one of its operative positions to illustrate the manner of laying mortar as designed.

Similar reference characters in the different figures of the drawings indicate corresponding elements or features of construction herein referred to in detail.

The new trowel is constructed principally of sheet metal and comprises a flat oblong main plate 1 having upturned side members 2 and 3 on the two opposite longer edge portions thereof. The main plate is uniform in width and sufficiently long to carry a large quantity of mortar, the width preferably being slightly less than the width of a standard brick. One end or shorter edge of the main plate has a rear end member 4 thereon that extends obliquely to the main plate. The side members are tapering and have straight edges 5 and 6 respectively to constitute gaging runners, the broader portions of the side members being connected to the end member 4 and extending beyond the latter, so that the narrower end portions 7 and 8 of the side members respectively are adjacent to the opposite end of the main plate. Thus the side members have relatively high portions 9 and 10 in proximity to the end member 4 to retain a large bulk of mortar, the edges 5 and 6 of the side members being on a plane that is oblique to the plane of the main member 1. The main plate 1 has short forward end portions 11 and 12 adjacent to the narrower ends 7 and 8 respectively of the side members, and the main plate has an extension 13 thereon, the extension having edges 14 and 15 that extend from the ends 11 and 12 respectively and converge to a point 16. The rear ends of the side members 2 and 3 preferably have rounded edge portions 17 and 18 respectively to permit the edges 5 and 6 to be drawn as runners smoothly along the top of the wall being

built. A handle 19 is rigidly secured to the outer side of the end member 4 and extends away on a plane between the plane of the main plate 1 and the plane of the edges 5 and 6, being preferably oblique angled to both planes, so that the trowel can be conveniently handled in either upright or inverted position.

In order that the manner of using the trowel to the best advantage may be readily understood a portion of a wall 20 is illustrated, 21 indicating the mortar joints thereof, the uppermost course having bricks 22, 23, 24, 25 and 26 spaced slightly apart as usual to receive the bonding mortar. To use the trowel it is handled by means of the specially arranged handle 19 so as to scoop a load of mortar therein and carry it to the place required where the trowel is dexterously turned over so as to deposit the mortar upon the upper course of the wall at the required place, after which the trowel is drawn backward while holding the edges 5 and 6 down on the tops of the bricks or stones, and with the trowel arranged slightly back from the edges of the bricks. As the trowel is drawn backward it produces a layer 27 of mortar with side portions 28 and 29 of uniform thickness, the layer being uniformly in width and slightly less than the width of the brick or stone, or so that the layer does not flow over the front edge of the wall and become wasted. As the trowel is moved backward the workman may apply pressure with one hand upon the main plate 1 which acts as a wedge to compress the mortar and force it compactly in place while the projecting nose portion 13 causes a longitudinal groove or depression 30 to be formed in the top of the layer of mortar, which is desired by the mason. The pressure produced on the mortar causes particles thereof to be forced down between the ends of the bricks or stones to form bonds 31 that unite with the bond portions 32 previously forced up in the joints when laying a course of bricks. When the succeeding course is laid upon the mortar, the mortar is pressed down slightly so as to be caused to spread out to the edges of the bricks, as in common practice, with the advantage that the bricks or stones may be more readily brought to a line on the uniform layer of mortar than when placed on a layer differing in thickness as has been the custom.

Having thus described the invention, what is claimed as new is—

1. A mortar-gaging trowel including a reversible flat plate having side gages and a slanting rear end on one side thereof and

having also a projecting front end, the side gages having edges to constitute runners, the edges being on a plane that is oblique to the body portion of the plate, and intersects the projecting front end of the trowel, and a handle on the outer side of the slanting rear end.

2. A mortar-gaging trowel comprising an oblong main plate having two low side plates on opposite edges thereof and having also a relatively oblique-angled rear end portion on one of its ends, the side plates being tapering and having their broader portions connected to the oblique-angled rear end portion of the main plate, the opposite end of the main plate having a projecting point thereon, and a handle secured to the outer side of the oblique-angled rear end portion of the main plate.

3. A mortar-gaging trowel comprising an oblong flat main plate, two low tapering side members on the opposite longer edges of the main plate, an end member on one of the shorter ends of the main plate in relatively inclined relation and connected to the broader portions of the side members, a grooving member on the opposite end of the main plate adjacent to the narrower ends of the side members, and a handle on the outer side of the end member extending on a plane that is between and oblique to the planes of the main plate and the plane of the edges of the side members.

4. A reversible smoothing and mortar-gaging trowel comprising a flat main plate that is oblong in plan, one of the shorter ends of the plate having a pointed projection central thereon, an inclined end member on the opposite end of the main plate that extends therefrom at an obtuse angle to the plate, two side members on the longer edges respectively of the main plate at right angles to the face of the plate, each side member being tapering and having its edge inclined to the plane of the main plate, the narrower portions of the side members being adjacent to the pointed projection, the broader portions of the side members being connected to the inclined end member and extending beyond it, and a handle secured to the outside of the end member and extending therefrom between the plane of the main plate and the plane of the inclined edges of the side members.

In testimony whereof, I affix my signature in presence of two witnesses.

OSCAR F. MANN.
